United States Patent Office

Des. 182,978
Patented June 3, 1958

182,978

ELECTRIC STAPLING MACHINE OR SIMILAR ARTICLE

Henry Ruskin, New York, N. Y., assignor to Swingline,
Inc., Long Island City, N. Y., a corporation of New
York

Application July 9, 1957, Serial No. 46,877

Term of patent 14 years

(Cl. D74—1)

Fig. 1.

Fig. 5.

Fig. 4.

Des. 182,978

PAGE 2

Fig. 1 is a side perspective view of an electric stapling machine illustrating my new design;

Fig. 2 is an enlarged side elevational view thereof, the side opposite thereto being similar in appearance;

Fig. 3 is an enlarged top plan view;

Fig. 4 is a front elevational view; and

Fig. 5 is a rear elevational view thereof.

I claim:

The ornamental design for an electric stapling machine or similar article, as shown and described.
